ABSTRACT OF THE DISCLOSURE

Corpse-preserving coffin having therein a cartridge containing a substance adapted to give off a gas, a mechanism operable from outside the coffin for opening the cartridge, a gas-escape valve, preferably provided with a pre-settable gate, and a filter interposed between the valve and perforations in a wall of the coffin. All parts except an actuating member for the opening mechanism being disposed inside the coffin, the latter can be transported, interred, placed in a vault or the like without specific arrangements, like an ordinary coffin.

This invention relates to a transportable sealed corpse-preserving coffin constructed, for example, of metal and so designed as to make it possible, on the one hand, to reduce or eliminate the evolution of decomposition gases and, on the other hand, to permit the evacuation of gases of this type which might be evolved in spite of the arrangements made.

The coffin as thus constructed comprises, in combination with means for ensuring leak-tightness, an automatic gas-escape valve with filter and calibrated or adjustable gate, and an internal capsule which is in communication with the internal chamber of the coffin. Within said capsule there is placed a closed cartridge containing a substance which is capable of giving off a gas other than oxygen and means operable from the exterior for initiating the opening of the cartridge.

The invention will be more readily understood from the following description which is given solely by way of example and not in any limiting sense, reference being made to the accompanying drawings, in which:

FIG. 1 is a schematic side view, with portions broken away, of a corpse-preserving coffin designed in accordance with the invention;

FIG. 2 is a longitudinal sectional view of a valve for the coffin, with a filter; and

FIG. 3 is a longitudinal sectional view of a capsule for the coffin, fitted with a gas cartridge.

Referring to FIG. 1, it can be seen that a metal coffin *a* is provided with a lid *b* which is fixed to a bottom portion *c* with interposition of a sealing joint *d*, there being secured to respective portions *3* and *21* of the coffin walls an automatic valve *e* and a valve casing *f* comprising gas-escape means (FIGS. 2 and 3, respectively).

The valve *e*, illustrated in FIG. 2, comprises a body *1* containing a valve gate and fixed within a casing *2* which is fixed to the coffin wall *3* and which terminates at the end portion thereof in a filter *17* through which the evolved gases are permitted to escape.

The body *1* is fixed within the casing *2* by means of a nut *6* which is screwed onto an externally threaded tube *4*, the extremity *5* of which constitutes a valve seat. The valve *e* includes a piston *7* which is fitted with a plug *8* either of rubber or suitable plastic material, the rod *9* of which is guided by its passage through a clamping nut *10*, a spring *11* being interposed between the head of the piston *7* and said clamping nut. Under these conditions, the force with which the piston *7* is applied against its

2

seat is easily regulated or adjusted by tightening or slackening off the nut *10*. A lock-nut *12* serves to secure the piston-rod in a chosen position. Thus the gate for the gas-escape valve is pre-settable.

5 The casing *2* comprises the filter *17* formed of a number of filtering layers placed between a metallic screen *13* and a perforated wall portion *14*. In the example which is illustrated, the casing *2* together with its filter *17* is joined to the wall *3* by means of a weld bead *16* and 10 the perforated wall portion *14* of the coffin is fixed by means of screws *15* in a manner which permits the ready removal of said wall portion *14* for the purpose of positioning the filtering layers.

In the example shown, the layers inside the filter *17* 15 comprise a flexible layer or sheath of woven cotton fabric, a layer of absorbent activated charcoal and a layer of vegetable sponge impregnated with chlorophyll.

Thus, in the event of overpressure within the coffin *a* above a predetermined value, the valve gate *e* opens and 20 the gases are discharged through the filter *17*, any unpleasant odor being nevertheless absorbed.

The coffin *a* is additionally provided with a device as shown in FIG. 3 which projects within the interior and which is fixed to the coffin wall *21*, the purpose of said 25 device being to reduce or prevent putrefaction processes. In this example, said device comprises a casing or capsule *20* which is secured, for example by welding, to the wall *21* of the coffin, inside this latter. Said casing *20* is pierced by a certain number of holes or perforations *22* 30 and is provided internally with a tubular sleeve *23* which is provided at the inner end with perforations or drilled holes *24*. There is thus formed between the casing *20* and the sleeve *23* an expansion chamber *25*.

The sleeve *23* is intended to receive a cartridge or 35 capsule *26* containing a gas which it is desired to introduce therein, for example compressed carbon dioxide gas. Said cartridge is fitted with an end-piece *27* which is closed off by an end-wall, diaphragm *28* or other frangible element formed, for example, of plastic material, 40 and the sleeve *23* is provided, on the one hand, with a pointed stud *29* and, on the other hand, with an internal screw-thread *30*. By tightening a nut *31* within the threaded portion *30*, the cartridge *26* is shifted further inside and the pointed stud *29* is thus caused to perforate the 45 diaphragm *28*. The gas accordingly flows into the coffin *a* after expansion within the chamber *25*. The air contained within the coffin is thus progressively driven through the automatic valve *e*.

As soon as the evolution of gas stops, the automatic 50 valve closes again and the coffin then contains only inert gas mixed with a small proportion of remaining air. In order to ensure that the proportion of oxygen which remains is sufficiently low, it is merely necessary to design the capacity of the capsule *26* accordingly or to provide a number of devices instead of only one, for discharging gases.

This replacement of oxygen by another neutral gas has the effect of reducing or even of preventing decomposition processes.

60 Instead of an inert gas, the gas which is given off can have antiseptic properties.

What I claim is:

1. A corpse-preserving coffin having walls as well as a well sealing lid and comprising, in combination, an 65 automatic gas-escape valve, one of said walls having first perforations therein, a filter interposed between said valve and said perforations for communication between said valve and the exterior of the coffin, an adjustable gate for said valve, a capsule having second perforations therein, projecting from another one of said walls toward the interior of the coffin and being in communication

therewith through said second perforations, the aforementioned valve, filter, gate and capsule being secured inside the coffin, a cartridge lodged in said capsule and containing a substance capable of giving off a gas which does not promote decomposition processes, said cartridge having a portion closed off by a frangible element, means for perforating said frangible element, so as to release said gas, and an actuating member for said perforating means, said member being the only part projecting outside the coffin.

2. A corpse-preserving coffin having walls as well as a well sealing lid and comprising, in combination, an automatic gas-escape valve, a filter connected between the outlet of the latter and the exterior of the coffin, an adjustable gate for said valve, a capsule having perforations therein, projecting from one of said walls toward the interior of the coffin and being in communication therewith through said perforations, a sleeve within said capsule and having holes therein, a cartridge lodged in said sleeve and containing a substance capable of giving off a gas which does not promote decomposition processes, said cartridge having a portion closed off by a frangible element, and means operable from the ex-

terior for perforating said frangible element, wherein said perforating means includes a pointed stud disposed opposite said frangible element internally at one end of said sleeve and a screw at the other end of said sleeve, said screw being operable from the exterior for the purpose of pressing said cartridge against said stud so as to perforate said frangible element and thereby open said cartridge.

UNITED STATES PATENT OFFICE
CERTIFICATE OF CORRECTION

Patent No. 3,435,494 Dated April 1, 1969

Inventor(s) Bernard Julien Pothier

It is certified that error appears in the above-identified patent and that said Letters Patent are hereby corrected as shown below:

The inventor's name should read correctly:

in the heading of the patent (above the drawing):

-- B. J. POTHIER -- instead of "J. P. BERNARD"; and

in the inner heading of the patent (above the description):

-- Bernard Julien Pothier -- instead of "Julien Pothier Ber-
nard".
